UNITED STATES PATENT OFFICE.

PALMER J. JONES AND PAUL D. SCHREIBER, OF PORT WASHINGTON, NEW YORK.

DESIGN FOR A DESK.

56,168.

Specification for Design. Patented Aug. 24, 1920.

Application filed June 4, 1919. Serial No. 301,812. Term of patent 3½ years.

To all whom it may concern:

Be it known that we, PALMER J. JONES and PAUL D. SCHREIBER, citizens of the United States of America, residing at Port Washington, New York, have invented a new, original, and ornamental Design for a Desk, of which the following is a specification.

In said drawing:

Fig. 2 is a front view of the same.

We claim—

The ornamental design for a desk, substantially as shown.

PALMER J. JONES.
PAUL D. SCHREIBER.
